D. H. BENJAMIN

NECKBAND AND ATTACHED COLLAR IRONING MACHINE

Filed Feb. 18, 1926

UNITED STATES PATENT OFFICE.

DANA H. BENJAMIN, OF CLEVELAND HEIGHTS, OHIO, ASSIGNOR TO THE AMERICAN LAUNDRY MACHINERY COMPANY, OF CINCINNATI, OHIO, A CORPORATION OF OHIO.

NECKBAND AND ATTACHED-COLLAR IRONING MACHINE.

Application filed February 18, 1926. Serial No. 89,167.

This invention relates to ironing machines, and more particularly to the class of ironing presses specially designed for ironing the neckbands, including collars if attached, of shirts.

In the commercial laundering of shirts it has been found expedient to iron the neckband, including the collar when attached, as a separate operation preliminary to ironing the remaining portions of each shirt; and presses have been devised and are at present widely used for performing this operation. Such a press necessarily must be provided with workholding and ironing surfaces sufficient to receive and cover a collar attached to a neckband; yet since a large number of shirts to be laundered are in the neckband style without collar, during a correspondingly large portion of the time only that part of the workholding and ironing surfaces covering the neckband alone are required.

It is the object of my invention to provide for this varying requirement of the workholding and ironing surfaces in a neckband ironing press in such a manner that the highest efficiency of the machine is not impaired when used for ironing either attached collars, or neckbands alone. The exact nature of the invention will be apparent from the following description referring to the accompanying drawings in which:

Fig. 1 is a side elevation, its upper part in section, of a neckband ironing press in which my invention has been incorporated; Fig. 2 is a rear elevation of the upper portion of the press shown in Fig. 1, and Fig. 3 is a rear elevation of the padded member, corresponding to Fig. 2, and showing the manner in which the invention is used.

In the drawings 1 represents the frame of the press, its upper portion being chambered and forming an arched yoke like head 2 through which steam is circulated, the head being polished upon its bottom surface. Mounted upon the rod 6 longitudinally slideable in the frame below the yoke 2 is a padded buck or work support 3 normally maintained in the position shown in Fig. 1 by the spring 4 acting through the lever 5, the end of which is joined with the end of the rod 6 by means of a clevis 7 fast upon the rod and serving also to limit its forward motion. At the base of the press is a pedal 8 by means of which, acting through the toggle joint 9, the buck

may be moved vertically to contact with the under or ironing surface of the yoke 2. The buck is maintained in this ironing position by the latch pedal 10 which when the pedal 8 is lowered engages it until released by the operator of the press, the latch pedal being urged clockwise (Fig. 1) by means not shown.

Operation of the press is as follows: Starting with the parts in the position shown in Fig. 1, the neckband of a shirt to be ironed is laid out and smoothed upon the buck 3, which is then pushed back under the head 2 by means of the handle 11, and the operator by depressing the pedal 8 until latched by pedal 10, raises the neckband to contact against the hot ironing surface of the head. After sufficient time for ironing has elapsed, the operator trips the latch pedal 10, releasing the buck from the head, and allowing the spring 4 to return the buck to the position shown, whereupon the shirt with the neckband ironed is removed.

What has thus far been described is old in the art, typical of many neckband presses, and is included for a more clear understanding of the operation of my invention, which comprises a mechanism for optionally limiting the forward travel of the buck 3.

Pivotedly mounted upon a stud 12 projecting from the rear of the frame of the press, is a bellcrank lever 13, one of its arms terminating in the handle 14, the other in a U shaped section 16 extending from the rear of the frame parallel with the rod 6 and spaced from the stud 12 so that the rod 6 is in its path of swing. A stud 15 limits the throw of the lever 13 in one direction, and the rod 6 in the other.

The longitudinal dimensions of the buck 3 and of the ironing surface of the yoke 2 are necessarily sufficient for ironing a collar attached to a shirt, and when the press is operated on a collar attached type of shirt, the operation is as hereinbefore described, the buck portion exposed in non-registering position being preferably just sufficient to take such shirt portion.

When a neckband only is to be ironed, however, only a small part of the available ironing surface is required, and I have made the longitudinal dimension of the U shaped spacing member 16 such that when the lever 13 is in the dotted position of Fig. 3 it will limit the forward motion of the clevis 7 and hence

the outward motion of the buck 3, to such an extent that only the then required area of the buck will be exposed beyond the yoke.

This greatly shortens the longitudinal travel of the buck, thus shortening the period of each ironing operation. Also, since the front edge of the buck serves as an aligning guide in placing the shirt to be ironed, the alignment is even better accomplished and more easily preserved when the projection and corresponding travel are lessened.

The operation of my invention is obvious. Suppose an attached collar in the press just closed upon it. During the pause in operation required in this position, the operator observes that the next shirt to be ironed is provided with neckband only. He then by means of the handle 14 throws the lever 13 from the position shown in Figs. 1 and 2 to the dotted position of Fig. 3 before tripping the pedal 10 to release the collar from the ironing surface. When released, the buck returns forward only sufficiently for the neckband to be placed upon it and consequently the operator need move the handle 11 only the corresponding short distance inward before again depressing the pedal 8 to clamp the press in ironing position.

If a collar is attached to the next shirt to be ironed, the operator then returns the lever 13 to the position of Figs. 1 and 2, whereupon when released, the buck 3 is returned outward to the position shown.

It has been found that my invention not

only considerably shortens the average time required in ironing shirts, but also improves the quality of work by obviating the difficulty heretofore encountered in properly aligning a neckband shirt upon a press of collar attached capacity.

Having thus illustrated and described my invention, what I claim is:

1. In a machine of the class described, a pair of ironing members relatively movable to open and close, and to and from registry, and means for adjustably limiting said movement from registry, to expose portions of the buck ironing member adapted to receive a shirt neckband with or without attached collar, whereby after return to registry the ironing members will close upon the neckband only or neckband with attached collar.

2. In a machine of the class described, a pair of ironing members relatively movable to open and close, and to and from registry, means for yieldably urging said members from registry, and means for adjustably limiting said movement from registry, to expose portions of the buck ironing member adapted to receive a shirt neckband with or without attached collar, whereby after return to registry the ironing members will close upon the neckband only or neckband with attached collar.

In testimony whereof I hereby affix my signature.

DANA H. BENJAMIN.
